(57) **CLAIM**

The ornamental design for a display screen or portion thereof with graphical user interface, as shown and described.

DESCRIPTION

FIG. 1 is a front view of a display screen or portion thereof with graphical user interface, showing our new design; FIG. 2 shows a second embodiment thereof; and, FIG. 3 shows a third embodiment thereof.

The dot-dash lines depict a display screen or portion thereof and form no part of the claimed design. All other broken lines depict portions of the graphical user interface and form no part of the claimed design.
